DOOR CLOSING CONTROL UNIT

Leslie L. Westcamp, Elk Creek, Calif.

Application March 13, 1939, Serial No. 261,511

5 Claims. (Cl. 292—71)

This invention relates in general to a unitary device adapted to be mounted on a door frame and arranged to control the closing of the door; the invention being directed in particular to an improvement in that type of door closing control unit which includes a substantially crescent-shaped, pivoted arm assembly having resilient door-engaging bumpers on each end thereof and actuated by a snap-action spring.

10 The principal object of the invention is to provide a door closing control unit of the type described which includes novel means to absorb the shock of, or check, closing movement of a door and to thereafter tightly close the door 15 without a noticeable slam and to yieldably hold the door in such position.

A further object of the invention is to produce a simple and inexpensive device and yet one which will be exceedingly effective for the 20 purpose for which it is designed.

These objects I accomplish by means of such structure and relative arrangement of parts as will fully appear by a perusal of the following specification and claims.

25 In the drawing similar characters of reference indicate corresponding parts in the several views:

Figure 1 is a sectional plan view of the unit as attached to a door frame and in cocked position; the door having engaged the inner roller bumper of the arm assembly and moved the floating frame inward.

Figure 2 is a plan view showing the position of the several parts as the inner bumper engages 30 between the door and door frame to check closing movement of the former.

Figure 3 is a top plan view showing the unit in position yieldably holding the door closed.

Figure 4 is a perspective view of the floating 40 frame detached from the device.

Referring now more particularly to the characters of reference on the drawing, the door closing control unit comprises a horizontal main frame 1 adapted to be mounted on a door frame 45 F adjacent the door D; this frame 1 comprising vertically spaced horizontal side plates 2, and integral back plate 3 and securing flanges 4 on the inner edges of said side plates. As is obvious, the frame is open adjacent the door 50 and at the outer end. The frame 1 is mounted on the door frame F a short distance laterally away from the edge adjacent the door whereby the intervening surface of the door frame provides a roller bumper stop 5 as will hereinafter 55 appear.

A floating frame indicated generally at 6 is mounted within the main frame and comprises, in integral relation, a back plate 7 disposed in face-to-face relation with plate 3 of frame 1, vertically spaced and aligned side arms 8 disposed horizontally and extending parallel to the door frame in face-to-face engagement with side plates 2 of frame 1, and a cross plate 9 extending between the outer edges of side arms 8; the cross plate 9 being turned inward short of 10 the free ends of arms 8 to form a spring anchor finger 10. The back plate 7 of the floating frame 6 is slotted lengthwise, as at 11, and rides on and is guided by a headed pin 12 undercut as shown and fixed on back plate 3 of frame 15 1; the undercut portion of said pin being engaged in slot 11 in relatively slidable relation. A vertical cross pin 13 extends between the outer 20 ends of arms 8 and through holes 14 therein; the projecting ends of the pin being slidably disposed in slots 15 cut in side plates 2 parallel to back plate 3 of frame 1.

A pair of substantially crescent-shaped arms 16 are disposed in vertically spaced relation and are pivoted intermediate their ends on pin 13 25 and between arms 8; this pivotal axis being disposed closer to the inner ends of said crescent arms than to the outer ends. These crescent arms 16 have a relatively small roller bumper 17 journaled between their outer ends on pin 18 30 and a relatively large roller bumper 19 journaled between their inner ends on pin 20; said arms being positioned with their concave edges adjacent the door, and being held in fixed relation by the several cross pins which extend there- 35 between. The roller bumpers are resilient and are preferably made of rubber.

A snap action tension spring 21 is formed with a hook 22 at one end which is engaged with anchor finger 10 on the sliding frame, while a hook 40 23 on the other end of the spring engages a cross pin 24 connecting the crescent arms 16 adjacent but spaced from roller 17. Between hook 22 and the spring proper, there is a portion 25 which is curved as shown and in a manner to 45 clear pin 13 regardless of the position of the crescent arms 16. The pivoted structure, including said arms 16 and the roller bumpers carried thereby, may be termed the roller 50 bumper assembly. As is apparent, the spring 21 is mounted in position to effect a snap action of the roller bumper assembly to alternate positions; the normal position being shown in Fig. 3 and wherein the roller 17 under the spring 55

tension yieldably engages the door with a closing force.

Upon opening movement of the door, roller 17 is moved outward rotating the roller bumper 5 assembly about pin 13 as an axis. With such movement the spring passes its dead center—which is pin 13—and when this occurs the assembly snaps to the cocked position and with roller 17 clear of the path of the door, as shown 10 in Fig. 1; the line of force of such spring when the assembly is so cocked being indicated by broken line A—A. The edge 26 of cross plate 9, formed by bending down spring anchor finger 10, provides a stop to limit further movement 15 of the roller bumper assembly beyond proper cocked position.

When the roller bumper assembly is cocked as above by initial opening movement of the door, the relatively large diameter roller bumper 19 20 carried by the other end of the crescent arms 16 has moved laterally and outwardly from its normal position (Fig. 3) to a position in the path of the door (Fig. 1). It is to be noted that the floating frame 6 is positioned as far outward 25 as possible, that is, pin 12 is engaged in the inner end of slot 11 and pin 13 in the outer end of slots 15 when the roller bumper assembly is in normal door holding position, or is cocked.

As the door swings toward closed position, it 30 engages roller bumper 19, immediately moving the floating frame inward as far as possible, as shown in Fig. 2. At the same time, the impact of the door on said bumper rotates the roller bumper assembly in a direction moving the roller bumper inward and laterally toward and into engagement with the door frame at 5 as the distance between pin 13 and the door frame is then less than the distance between said pin and the door-engaging surface of the roller 19. 35 This rotation of the roller bumper assembly to the point where roller bumper 19 engages the door frame has shifted the line of force of the spring, indicated by broken line B—B past dead center position and the spring acts on the roller bumper assembly in a direction to return the same to normal position.

However, this does not immediately occur as roller 19 urged by the spring and by the closing door has abutted against door frame portion 5 40 as above described. The motion of the door is then arrested or checked and the shock absorbed by roller 19, the rebound of the door and of the roller releasing the roller from between the door and door frame portion 5. The spring then snaps 45 the assembly to normal position and with roller 17 striking and tightly but yieldably closing the door. This occurs for the reason that as the roller 19 releases from the door and door frame and begins its return to normal position, the 50 outward force acting on the roller bumper assembly, and arising from the inclined plane effect of the outer surface of the door frame with respect to the roller bumper 19 and pivot pin 13, causes the floating frame to move toward its 55 outward and normal position. The roller bumper 19 and the adjacent portions of its supporting elements then swing away from the door and into main frame or housing 1. Such outward motion of the floating frame is assisted by the 60 reaction of the roller 17 if the door rebounds sufficiently from checking engagement with roller bumper 19, and is brought to final position by the engagement of the roller 17 with the outer surface of the door for its tight but yield- 65 able closing.

The above described unit functions smoothly, quietly and yet efficiently to check and close a door; the structure of the unit being simplified as well as sufficiently rugged and durable to assure long life without necessity of repair or 5 adjustment.

From the foregoing description it will be readily seen that I have produced such a device as substantially fulfills the objects of the invention as set forth herein. 10

While this specification sets forth in detail the present and preferred construction of the device, still in practice such deviations from such detail may be resorted to as do not form a departure from the spirit of the invention, as defined by the appended claims. 15

Having thus described my invention, what I claim as new and useful and desire to secure by Letters Patent is:

1. In a door closing control unit, a support 20 adapted to be mounted on a door frame, a snap action bumper assembly including an arm having a bumper on one end thereof, a pivot for the arm, said arm being arranged for swinging movement from a position with the bumper in 25 the path of the door to a position clear thereof and spaced in front of the door frame, and means mounting said arm pivot in connection with the support for limited inward and outward movement relative to the door frame; the 30 arm between said pivot and the said bumper being of such length that when the pivot is in innermost position and the arm swings inward, the bumper engages the door frame whereby to momentarily check inward motion of the bumper 35 and following door.

2. A unit as in claim 1, in which said last named means comprises a floating frame mounted on the support for inward and outward movement relative thereto; the arm pivot being 40 mounted in connection with said floating frame.

3. In a door closing control unit, a support adapted to be mounted on a door frame, a floating frame carried by said support and arranged for limited inward and outward movement relative to the door frame, a snap action bumper assembly including an arm having a bumper on one end thereof, and means pivoting the arm on the floating frame for inward swinging movement from a position with the bumper in 50 the path of the door to a position clear thereof and spaced in front of the door frame; the arm between its pivotal axis and the said bumper being of such length that when the floating frame is in innermost position and the arm swings inward, the bumper engages the door frame whereby to momentarily check inward motion of the bumper 55 and following door.

4. A device as in claim 3 in which the support includes a pair of spaced sides extending 60 out from the door frame, and a connecting back plate, and in which the floating frame comprises a back plate having a longitudinal slot therein and disposed in face-to-face engagement with the inner surface of the support back plate, a pin 65 fixed on the latter and engaging in said slot, side arms formed with the back plate of the floating frame and projecting toward the door; said means comprising a pivot pin extending between the arms and therebeyond at both ends, the 70 sides of the support having elongated slots therethrough parallel to the back plates, the pin at its ends engaging in said slots in slidable relation thereto.

5. In a door closing control unit, a main frame 75

adapted to be mounted on a door frame, a floating frame carried by the main frame and arranged for limited inward and outward movement, said floating frame including a pair of spaced arms projecting toward the door and a cross plate extending between and connecting said arms, a snap action bumper assembly including a pair of substantially crescent shaped arms having a roller bumper secured between the arms at each end, means pivoting the assembly intermediate its ends between the arms of the floating frame and for swinging move-

ment of the door checking one of said bumpers from a position in the path of the door inward to a position clear thereof and spaced in front of the door frame; the arms of the assembly between its pivotal axis and said one bumper being of such length that when the floating frame is in innermost position and upon such movement of the bumper, the latter engages the door frame whereby to momentarily check such motion of the bumper and following door. 10
